UNITED STATES PATENT OFFICE.

CHARLES J. BRANCH, OF PHILADELPHIA, PENNSYLVANIA.

CONCRETE ANCHOR OR INSERT.

1,352,245.

Specification of Letters Patent.

Patented Sept. 7, 1920.

Application filed May 27, 1916. Serial No. 100,178.

To all whom it may concern:

Be it known that I, CHARLES J. BRANCH, a citizen of the United States, residing in the city and county of Philadelphia, State of Pennsylvania, have invented a new and useful Concrete Anchor or Insert, of which the following is a specification.

My invention relates to a novel construction of a concrete anchor or insert, which is adapted to be readily and conveniently supported and surrounded with concrete and is constructed with upright and downwardly converging walls collocated in such a manner that a conical internal nut chamber is provided into which standard nuts of different sizes may be inserted, turned and then inverted into a horizontal position, so as to be securely retained in the desired position and prevented from rotation during the screwing of a bolt into the nut, means being thus provided for the ready disengagement of the bolt from the nut and also for enabling the nut to be readily removed from the nut chamber or nuts of varying sizes to be inserted and withdrawn from said nut chamber according to requirements.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a concrete anchor or insert embodying my invention.

Fig. 2 represents a section on line 2—2 Fig. 1.

Fig. 3 represents a sectional view similar to Fig. 2, showing a nut in the act of being inserted endwise into position within the nut chamber.

Fig. 4 represents a sectional view similar to Fig. 2, but showing in elevation the nut turned from the position seen in Fig. 3 and in engagement with the walls of the nut chamber and its coacting bolt.

Fig. 5 represents a sectional view similar to Fig. 4 but showing a smaller nut in position.

Fig. 6 represents a section on line 6—6 Fig. 5.

Fig. 7 represents a bottom plan view of Fig. 1.

Similar numerals of reference indicate corresponding parts in the figures.

Referring to the drawings:

1 designates the wedge or similar shaped body or box of my novel concrete anchor or insert, the same comprising the top 2, having 65 the substantially parallel side walls 3 and the end walls 4, which converge downwardly so that an open mouth 5 preferably of greater length than width is formed at the bottom of the body, the latter having the 70 flanges 6 projecting oppositely therefrom, said flanges being provided with slots 7, for the reception of suitable fastening devices, whereby the anchor or insert can be conveniently secured in the desired position to 75 a suitable support.

8 designates a standard nut, which is preferably square and is adapted to be inserted in the open mouth or opening 5, as seen in Fig. 3, it being apparent that the width of 80 said mouth, while slightly greater than the thickness of the nut 8, is so proportioned that it is narrower than the breadth of said nut, so that when the latter is turned into the position seen in Figs. 4 and 5, which can 85 be readily done by turning the nut in the direction of the arrow *a* seen in Fig. 3, the nut readily assumes a horizontal position and is prevented from rotation by the contact of its edges 9 with the contiguous inner walls 10 90 of the nut chamber 11 contained within the body 1, as will be apparent from Fig. 6.

The relative proportions of the mouth 5 with respect to the nut 8, will be understood from Fig. 6, and I preferably employ a 95 standard square nut, as being best adapted to coact with the internal walls of the nut chamber 11, although other shapes of nuts may be employed. The nut 8 having been inserted into place as described with respect 100 to Figs. 3 and 4, the bolt 12 can be readily screwed into position, as will be understood from Figs. 4, 5 and 6, said bolt having the eye or opening 13 therein, for the reception of rods, bars, hooks, or the like, which may 105 be employed in building construction.

I preferably employ the flanges 14, which project laterally from the top 2 of the body 1, which is adapted to be inserted in or surrounded by the body of concrete 15.

It will be seen from the foregoing that by reason of the downward convergence of the end walls 4 of the wedge or similar shaped body 1, the anchor or insert is prevented 5 from dislodgment with respect to the surrounding concrete, and by the employment of the flanges 14 and 6, additional laterally extending anchoring elements are provided, which will hold the anchor or insert rigidly in position after being surrounded with concrete, as is evident. By reason of the 10 contour of the nut chamber 11, it will be apparent that the nut 8, after having been initially inserted endwise into position in the manner indicated in Fig. 3 and then turned 15 into the horizontal position seen in Figs. 4, 5 and 6, is prevented from turning, while the bolt 12 is screwed thereinto and in addition a large size nut and coacting bolt, as indicated in Fig. 4, or a smaller size nut and bolt, as indicated in Fig. 5, can be readily employed within or in conjunction with the same standard sized anchor or insert body.

By the employment of the slotted flanges 20 25 6, I am enabled to conveniently secure the anchor or insert in any desired position upon a suitable support.

My novel anchor or insert can be cheaply manufactured, is not liable to get out of order and affords a ready and convenient means for enabling bolts 12 of different sizes to be supported at the desired point, as will be apparent to those skilled in the art.

It will be understood that if desired the 30 35 flanges 14 can be omitted and that the contour of the flange 6 can be changed, according to requirements. While I have shown the bolt 12 as provided with an eye 13 there- 40 in, it will be understood that any other kind of a bolt or suspension device having a forged head or the like can be employed in lieu of the bolt 12.

If desired, I may employ a pipe or rod in lieu of the bolt 12, in conjunction with the 45 50 nut 8, the latter being suitably tapped for the reception of the upper end of the pipe, rod or the like.

I desire to call special attention to the fact that in all the embodiments of my device, as seen in Figs. 4 and 5, the edge 9 of 55 the nut, which may be square or other shape, rests directly upon the inner wall 10 and not upon inwardly projecting flanges or lugs located at or near the mouth 6, as has heretofore been the practice.

By my construction seen in Figs. 4 and 5, wherein I support the nut directly upon the juxtaposed downwardly converging walls, it will be seen that the pull upon the 60 nut caused by the load which may be exerted upon the inner walls 10 will be in every case resisted by the bed of concrete surrounding the anchor or insert, so that a very heavy load can be supported from the 65 nut 8 without injuring or distorting the

body of the anchor or insert, since the strain of the load being against the concrete at the sides of the insert insures increased carrying strength.

It will be apparent from the foregoing 70 that it is impossible to pull the anchor or insert out of the concrete 15.

It will also be apparent that while I have shown the walls 3 as being upright or substantially parallel, the contour of said walls 75 can be changed, if desired.

It will now be apparent that I have devised a novel and useful concrete anchor or insert, which embodies the features of advantage enumerated as desirable in the 80 statement of the invention and the above description, and while I have, in the present instance, shown and described a preferred embodiment thereof which will give in practice satisfactory and reliable results, it is 85 to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, a wedge-shaped anchor or insert, comprising 95 a closed body portion, having a closed top member provided with parallel vertical rectilinear side walls, oppositely located rectilinear end walls converging downwardly from said top so as to form an angular nut 100 chamber between said walls, whose internal area increases upwardly and is greatest at its top, oppositely located top anchoring flanges forming a continuation of said top and overhanging said closed vertical walls, 105 slotted bottom anchoring flanges projecting laterally from the bottom of said vertical flanges, an open mouth in the bottom of said body of greater length than width, the longest dimension of said mouth extending 110 at a right angle to said vertical side walls, and a standard nut inserted endwise there- 115 in, said nut when turned into a horizontal position being supported upon said inner converging walls at a point above said mouth.

2. In a device of the character stated, a wedge-shaped anchor or insert, comprising a closed body portion having a closed top member provided with parallel vertical rectilinear side walls, oppositely located rectilinear end walls converging downwardly from the top so as to form an angular nut chamber between said walls whose internal area is greatest at its top, oppositely located 125 top anchoring flanges forming a continuation of said top and overhanging said vertical walls, slotted bottom anchoring flanges projecting from the bottom of said vertical flanges and an open mouth in the bottom 130

of said body of greater length than width, the longest dimension of said mouth extending at a right angle to said vertical side walls, in combination with a standard nut 5 inserted endwise therein, said nut when turned into a horizontal position, being supported upon said inner converging walls at

a point above said mouth and a bolt supported by and in engagement with said nut, and having an eye in its lower end.
